UNITED STATES PATENT OFFICE

ROBERT D. LINDSAY, OF DENVER, COLORADO

BRICK-ROUGHENING MACHINE

Application filed September 11, 1926. Serial No. 134,870.

This invention relates to improvements in pressed brick machines and has reference more particularly to machines for marking the surfaces of the brick so as to improve the 5 appearance of the finished wall.

In the manufacture of pressed brick, it is often desirable to scratch the surface of the brick so as to prevent the flat plane appearance of the finished wall. This has usually 10 been accomplished by hand and has therefore added considerably to the cost. As pressed brick are formed from a powdered material that is but slightly moistened by subjecting the material to great pressure, the 15 outer surface cannot successfully be marked or scratched without first being moistened. The proper moistening of the surface is a matter that involves considerable difficulty as moisture should be supplied only to the 20 surface that is to be roughened and must also be applied evenly and in the proper amounts only.

I have found that the moisture can be applied most satisfactorily by means of felt 25 rollers arranged in pairs and having contacting surfaces. One of these rollers receives water from a suitable supply, while the other roller contacts with the brick and in this manner an even distribution of moisture over the 30 surface of the brick is obtained.

It may be mentioned here that pressed brick are entirely different from common wet 35 clay brick and that an apparatus that will operate successfully in connection with the latter will not operate successfully with the former. This is due to the fact that the slightly moist pressed brick will crumble very readily when marked with a scribe, 40 while a wet clay brick will not. This makes it essential to carefully moisten the surfaces to be scribed and it is more particularly to this additional means to which this invention relates.

45 My invention also relates to improvements in the specific construction of the apparatus employed, all of which will hereinafter be described in detail and claimed and for this purpose reference will now be had to the accompanying drawing in which the preferred

embodiment thereof has been illustrated and in which:

Fig. 1 is a top plan view of my improved machine;

Fig. 2 is a side elevation thereof;

Fig. 3 is a section taken on line 3—3, Fig. 1;

Fig. 4 is a section taken on line 4—4, Fig. 1;

Fig. 5 is a section taken on line 5—5, Fig. 1;

Fig. 6 is a section taken on line 6—6, Fig. 2;

Fig. 7 is a section taken on line 7—7, Fig. 6; 60 and

Fig. 8 is a section taken on line 8—8, Fig. 2.

Numerals 1 and 2 represent the two side members of the supporting frame. These members are connected at various points 65 along their length by means of angle irons 3. These side members are supported from some supporting surface by means of legs 4 of which there may be as many as necessary.

Secured to the side members 1 and 2, near 70 one end of each are bearings 5 within which is rotatably mounted a shaft 6 to which I have secured two sprocket wheels 7. Spaced from the bearings 5 are two other bearings 8 in which is journalled a shaft 9. This shaft 75 carries two sprocket wheels 10 which are similar to the sprocket wheel 7 on shaft 6. Secured to an extension of shaft 9 is an enlarged sprocket wheel 11 to which the power, from the motor or engine, is delivered to 80

the machine. A conveyor belt comprising two sprocket chains 12, each of which cooperates with corresponding sprocket wheels 7 and 10 is provided for the purpose of moving 85 bricks along the machine. These sprocket chains 12 have special links 13 spaced equidistantly apart. These links are provided with upwardly extending arms 14 to which a plate 15 is secured. This part of the mechanism will be referred to and more fully explained hereinafter. Secured to the transverse angles 3 are channels 16 and 17, which 90 serve as supports for the sprocket chains 12. The sprocket chains 12 are spaced apart a distance which is less than the length of a brick so that when the bricks are laid in place transversely of the conveyor, they will rest on the sprocket chain in the manner shown in Fig. 5. If the wheel 11 and shaft 9 are rotated in a clockwise direction, when 95

viewed as in Fig. 2, the sprocket chains 12 will move in the direction of the arrow in Fig. 2 so that any bricks that rest on the sprocket chains will be moved from left towards right in Fig. 1. The plates 15 which are secured to the special links 13 will naturally engage the bricks in the manner indicated in Fig. 5. As the operation of the machine causes more or less resistance to the movement of the bricks, a considerable pressure has to be applied to the latter by means of the plate 15 and unless special means is provided, the plate 15 will rotate slightly out of plumb position. I have therefore provided means for holding the plate so that it will retain its vertical position, regardless of the force exerted by it during the operation. This last named means comprises two inverted angle irons 18 which are secured to the side of the channels 16 and 17 above referred to. An L shaped bracket 19 is secured to the rear surface of each plate 15 and the horizontal portion of this is perforated for the reception of a bolt 20, whose lower end extends below the horizontal flanges of the angles 18 and is provided with bearings 21 for the rollers 23. These rollers lie beneath the horizontal flanges of the angles 18 and will be drawn up into contact with these flanges whenever a force is applied to the plates which tend to rotate them in a counter clockwise direction (Fig. 5).

Two brackets 24 of identical shape and size are secured to the side members 1 and 2 by means of bolts 25. A downwardly extending steel bar 26 is secured to the top of each of these brackets and is provided with openings near its lower end for the reception of the axle 27 of the felt roller 28. This roller is mounted in such a position that the axle 27 extends transversely of the direction of movement of the conveyor belt and at such a height that the roller will rest or come in contact with the upper surface of the bricks as the latter are being moved underneath the same by the action of the conveyor belt 12. The second felt roller 29 is pivoted to the free ends of the spring supports 30 and is held in contact with the surface of the roller 28 by means of the force exerted by said springs. Pipe 31 that is connected to a suitable source of water supply is secured to the upper ends of the brackets 24 and is provided with branch pipes 32 that extend to and terminate above the upper surface of the roller 29. Each of these branch pipes is provided with a valve 33 by means of which the rate of flow of water may be regulated. When the machine is in operation water is caused to drip slowly through the pipes 32 and fall onto the upper surface of the roller 29 which thereby becomes wetted and some of the water is transferred to the roller 28 at the point where these two rollers contact. By this means the

roller 29 becomes uniformly wet and is therefore enabled to uniformly moisten the surface of the brick with which it comes into contact.

Since it is my intention to roughen the ends of the bricks as well as the upper surface thereof, I have provided a felt roller 34 which is pivoted so as to rotate about a vertical axis in the manner indicated in Figs. 1 and 2. A pipe 35 is connected to the pipe 31 and controlled by means of a valve 36 which controls the rate at which the water flows through pipe 35. The water that escapes from the pipe 35 keeps the surface of the roller 34 properly moistened so that this in turn will moisten the ends of the brick. As roller 34 rotates on a vertical axis, it is evident that the water will be quite uniformly distributed over the outer surface by the action of the gravity.

After the bricks have passed the moistening apparatus they are ready to be roughened and for this purpose I have provided a scribbling apparatus comprising a plurality of scribes and I will now proceed to describe this means. Bars 37 are secured to the upper side of the bracket 38 by means of supporting bolts 39 in the manner shown in Figs. 2 and 5. The bars 37 serve to support two transversely and longitudinally adjustable bars 40 and 41 which are provided with a plurality of openings through which the scribes 42 extend. These scribes are arranged in two rows and have their upper ends secured together by means of a clamping device which has been indicated as a whole by reference numeral 43. The lower end of these scribes is adjusted vertically so that they will come below the upper surface of the bricks a sufficient distance to roughen the latter by means of parallel grooves in the manner indicated in Fig. 5. The adjustable construction applied to the members 40 and 41 makes it possible to adjust the scribes relative to each other so that the lines or grooves will be properly spaced. By using two groups of scribes, it is evident that the scribes can be placed twice as far apart as if they were placed in one row and this reduces or minimizes the danger of breaking the surface of the brick.

For the purpose of roughening the ends of the brick, I have provided another group of scribes which have been indicated by numeral 44. These scribes have their front ends supported by a bar 45, whose ends are pivotally connected to the horizontal supporting members 46 and 47 and have their free ends held in alignment by means of a clamping device 48. Secured to the upper surface of the bracket 38, is a bar 49 which is provided with two adjusting screws 50, whose ends engage the bar 45 for the purpose of moving the latter to the desired position.

By means of this adjustment it is possible to locate the points of the scribes 44 in the proper relation with respect to the ends of the brick (Fig. 6).

5 By reference to Fig. 7 it will be noticed that the supporting bar 45 is really composed of three separate bars, the center bar, which has been indicated by numeral 51, is slideable with respect to the others and can be adjusted 10 by means of the nut 52. It is evident that by these means the scribes 44 can be firmly clamped and held in the desired position with respect to the support 45. After the bricks have passed beneath the moistening apparatus, they are moved towards the roughening device which has just been described and as they pass the points of the scribes, the latter penetrate the surface of the brick and cut parallel grooves therein. Unless the brick 15 surfaces have been properly moistened, the scribes will break the surface in an irregular manner, whereas, if the brick surfaces have been moistened just right, the scribes will merely cut clean grooves which give the 20 surface of the brick a striated effect. After the brick has passed the roughening device, they are then ready to be transferred to the kiln and for this purpose I have provided another conveyor comprising two belts 25 53 and 54 which cooperate with belt wheels on the shaft 55 and on the shaft 55'. These belts are made to travel faster than the sprocket chains 12 so that they will tend to separate the bricks as the latter are delivered to the belts by means of a chain conveyor. Another conveyor 56 carries the 30 brick to any desired position where they are loaded on two cars or other transporting means and are transported to the kiln.

40 For the purpose of adjusting the roller 34 with respect to the ends of the brick and to subject the latter to the necessary amount of pressure, I have mounted the roller 34 in a U-shaped bracket 57 whose ends are pivoted 45 at 58 (Fig. 2). A bell crank lever 59 is pivoted to a stationary part at 60 and carries a pin 61 that engages the end of the bracket 57. The other arm of this bell crank carries a weight 62 which causes the pin 61 to move 50 towards the bracket 27 in such a manner that the roller 34 will be pressed against the ends of the brick. By moving the weight 62 along the horizontal arm of the lever 59, this pressure may be varied to obtain the best results.

55 From the above it will be apparent that I have produced a device by means of which pressed brick may be satisfactorily striated and that this operation is made successful by means of the means that I have provided 60 for uniformly wetting the surface of the brick to be roughened.

Having described my invention, what I claim as new is:

1. A machine for roughening the surface of 65 pressed brick comprising, in combination, a

supporting surface, means for moving brick along said surface, means for moistening the upper surface of said brick, a plurality of scribes and means for holding them in such a position that they will come into contact with the brick as the latter move past the scribes.

2. In a machine for roughening the surface of pressed bricks having means for supporting bricks, means for moving said brick along said support and a plurality of scribes held in position to contact with the surfaces of the bricks as the latter are moved past the scribes, the combination with the above of a felt roller mounted to rotate about an axis transverse to the direction of movement of the brick and so located as to come into contact with the upper surfaces of the bricks and means for applying water uniformly over the surface of the roller whereby the surfaces of the bricks that contact with the roller will be uniformly moistened.

3. In a machine for roughening the surface of pressed bricks having means for supporting bricks, means for moving said brick along said support and a plurality of scribes held in position to contact with the surfaces of the bricks as the latter are moved past the scribes, the combination with the above of two felt rollers mounted on parallel axes and contacting with each other along their outer surface means for securing said rollers in place so that one roller will contact with the upper surface of the brick as they are carried along the conveyor and before they are acted upon by the scribes.

4. In a machine for roughening the surface of pressed bricks having means for supporting bricks, means for moving said brick along said support and a plurality of scribes held in position to contact with the surfaces of the bricks as the latter are moved past the scribes, the combination with the above of a framework, a roller supported on said framework so as to be rotatable about an axis substantially perpendicular to the direction in which the bricks travel and adapted to contact with the upper surface of the bricks, a second roller supported by said framework and adapted to contact with the first named roller, means for forcing the second roller against the first roller and means for applying water to the second roller so as to moisten the first named roller.

5. In a machine for roughening the surface of pressed bricks having means for supporting bricks, means for moving said brick along said support and a plurality of scribes held in position to contact with the surfaces of the bricks as the latter are moved past the scribes, the combination with the above of a framework, a roller supported on said framework so as to be rotatable about an axis substantially perpendicular to the direction in which the bricks travel and adapted to contact with the

upper surface of the bricks, a second roller supported by said framework and adapted to contact with the first named roller, means for forcing the second roller against the first roller, means for supplying water to the second roller so as to moisten the first named roller, a third roller supported on said framework, said roller being rotatable about a vertical axis, means for applying water to the surface of the third roller and means for forcing this roller against the ends of the bricks.

6. In a machine for roughening the surface of bricks having a conveyor for moving the bricks along a support having a horizontal surface and past a support containing a plurality of scribes, the combination with said support and conveyor of a framework supporting two rollers having felt surfaces, one of said rollers being so supported that it will contact with the upper surface of the bricks as they are moved towards the scribes, the second roller being supported so as to be rotatable about an axis parallel with the first roller and having its surface in contact with the surface of the first roller and means for applying water to the second roller.

In testimony whereof I affix my signature.
ROBERT D. LINDSAY.
